CHAIR OR SIMILAR ARTICLE

Florence S. Knoll, New York, N.Y., assignor to Knoll
Associates, Inc., New York, N.Y., a corporation of
New York

Application November 25, 1957, Serial No. 48,645

Term of patent 14 years

(Cl. D15—1)

Fig. 1.

Fig. 2.

Fig. 3.

Fig. 4.

Fig. 1 is a perspective view of a chair embodying the new design showing the front and one side thereof;

Fig. 2 is a side elevation view of the chair of Fig. 1 on a reduced scale showing the side thereof opposite the side shown in Fig. 1;

Fig. 3 is a rear elevation view of the chair of Fig. 2; and

Fig. 4 is an enlarged fragmentary view of one corner of the chair showing the recess between the seat and frame in greater detail.

The dominant features of my design reside in those portions shown in full lines on the drawing which define

the recess between the bottom of the seat and the top of the frame below the seat.

I claim:

The ornamental design for a chair or similar article, substantially as shown and described.
